(57) **CLAIM**

The ornamental design for an eyeglasses case, as shown and described.

DESCRIPTION

FIG. 1 is a bottom perspective view of an eyeglasses case. FIG. 2 is a top perspective view of the eyeglasses case of FIG. 1 showing an actuator in an eyeglasses stored position. FIG. 3 is a bottom view of the eyeglasses case of FIG. 1. FIG. 4 is a top view of the eyeglasses case of FIG. 1 showing the actuator in the eyeglasses stored position.

FIG. 5 is a first side view of the eyeglasses case of FIG. 1 showing the actuator in the eyeglasses stored position.

FIG. 6 is a second side view of the eyeglasses case of FIG. 1 showing the actuator in the eyeglasses stored position.

FIG. 7 is a back view of the eyeglasses case of FIG. 1 showing the actuator in the eyeglasses stored position.

FIG. 8 is a front view of the eyeglasses case of FIG. 1 showing the actuator in the eyeglasses stored position.

FIG. 9 is a top perspective view of the eyeglasses case of FIG. 1 showing the actuator in an eyeglasses loading position.

FIG. 10 is another bottom view of the eyeglasses case of FIG. 1, but with the unclaimed eyeglasses in the position seen in FIG. 9.

FIG. 11 is a top view of the eyeglasses case of FIG. 1 showing the actuator in the eyeglasses loading position; and, FIG. 12 is a view of the second side of the eyeglasses case of FIG. 1 showing the actuator in an eyeglasses loading position.

Portions of the drawings shown in broken line depict environmental structure associated with the eyeglasses case. The broken lines and environmental structure they depict form no part of the claimed design.
